UNITED STATES PATENT OFFICE.

CHARLES M. GREISING, OF ST. PAUL, MINNESOTA, ASSIGNOR, BY MESNE ASSIGNMENTS, TO INTERNATIONAL HARVESTER COMPANY OF NEW JERSEY, A CORPORATION OF NEW JERSEY.

MACHINE FOR TREATING FIBER.

1,225,804.

Specification of Letters Patent. Patented May 15, 1917.

Application filed October 9, 1913. Serial No. 794,255.

To all whom it may concern:

Be it known that I, CHARLES M. GREISING, a citizen of the United States, residing at St. Paul, in the county of Ramsey and 5 State of Minnesota, have invented certain new and useful Improvements in Machines for Treating Fiber, of which the following is a full, clear, and exact specification.

This invention relates to machines for 10 treating fiber in the manufacture of twine, and more particularly to means for controlling the supply of oil or special fluid compound with which the fiber is treated.

In the manufacture of twine it is necessary to run the fiber through a preparing process. This is done by drawing the fiber through various machines for softening and combing the fiber and providing it with oil or special fluid compound for the purpose of preventing destructive results occasioned by insects found in grain fields. The fluid, which is sprinkled onto the fiber as it passes through one or more of the preparing machines, is supplied at a uniform 20 rate so that the finished product will have a uniform appearance and be of the same quality throughout. It is frequently necessary for the machines or haulers through which the fiber is fed to be stopped. When 25 these machines are stopped it is of importance that the treating fluid supply to the fiber should be discontinued to avoid wasting the fluid, in addition to the reasons given above. This, however, has not been 30 done heretofore with any degree of accuracy, for the reason that in many instances the operator has failed to shut off the supply of fluid when the machine has been stopped and has neglected to turn on the 35 supply fluid when the machine has been started to operate.

It, therefore, is the object of my invention to control the supply of treating fluid to material passing through a fiber treating 45 machine to meet all of the requirements for successful commercial results.

This object is accomplished by providing in such a machine means for controlling automatically the supply of treating fluid 50 to material passing through the machine.

The invention is illustrated on the accompanying sheets of drawings, in which—

Figure 1 is a fragmentary front elevation of a machine equipped with my invention;

55 Fig. 2 is a side elevation of the same;

Fig. 3 is a plan view of the treating fluid attachment; and

Fig. 4 is a sectional view of the fluid receptacles and associated parts taken in the plane of line 4—4 of Fig. 3.

66

The various novel features of my invention will be apparent from the description and drawings and will be particularly set forth in the appended claims.

The fiber treating machine proper includes side frame members 10, in which is journaled a shaft 11 on one end of which are secured a loose pulley 12 and a tight pulley 13. Also mounted upon said shaft 11 is a roller 14 for feeding the fiber or material from the machine or hauler through a spout 15.

Secured to the side frame members 10 is a supplemental supporting frame 16 to which bracket members 17 are secured. 75 Suspended by straps 18 and supported thereby is a fluid receptacle 19 having an overflow 20. Supported in a suitable manner directly above this receptacle 19 is a smaller fluid containing receptacle 21, into 80 which treating fluid continuously flows through a supply pipe 22, the fluid overflowing a baffle plate 23 within the receptacle 21 when the fluid has attained a predetermined level. The fluid in receptacle 85 21 overflows through a pipe 24 back into the fluid circulating system 25. The lower receptacle 19 is also provided with a main outlet 26, which is controlled by a valve having a handle 27. The handle 27 and corresponding valve are turned to drain receptacle 19 when the operator observes that the fluid is passing out through overflow 20.

90 Adapted to rotate in the fluid or oil compound within the receptacle 21 is a supply- 95 or conveying roller 28 mounted upon and secured to a shaft 29 journaled in bearings 30 of the bracket members 17. Mounted upon the same shaft 29 is a pulley 31, by means of which the roller 28 may be 100 driven continuously independent of the operations of the machine itself. A scraper 32, which is secured to a shaft 33 journaled in bearings 34 in the bracket members 17, is maintained in engagement with the roller 105 28 at all times for scraping the treating fluid off the roller by means of an arm 35 provided at its end with a weight 36. As shown in Fig. 2 of the drawings, the fluid which is scraped off of the roller 28 passes 110

down over the scraper 32 onto a conductor 37, which is supported in a suitable manner, the fluid passing from said conductor onto the material passing from the machine 5 through the spout 15. It is apparent that if some provision were not made the fluid would continue to pass down onto the material passing through the spout or onto the spout itself, whether or not the machine proper 10 was in operation. To overcome this objectionable feature, I have provided a shield 39 which is secured to a shaft 40 journaled in bearing members 41, the shield being adapted to be swung into the positions shown in 15 Figs. 2 and 4 of the drawings. When the shield 39 is in the position shown in Fig. 2, the fluid is permitted to pass down onto the conductor 37 and from there onto the material passing through the spout, and when 20 the shield 39 is swung into the position shown in Fig. 4, the fluid which is scraped off of the roller 28 by the scraper 32 and which flows onto the shield 39, is directed into the lower receptacle 19, thus preventing 25 further flow of the fluid onto the material passing through the machine.

As stated above, it is of particular importance that the treating fluid be prevented from flowing onto the material in the 30 machine when the machine itself is in a state of rest. In order to prevent this flow of fluid onto the material when the machine is at rest and to permit the flow of fluid onto the material when the machine is 35 in operation, I have provided unitary control means to accomplish the desired result with accuracy and certainty. This unitary control means includes a manually operated belt shifter 45, to which is connected a pivotally mounted bell crank lever 46, to one 40 end of which is connected a link 47, which in turn is pivotally connected to an arm 48, the latter being secured to the shaft 40 upon which the shield 39 is secured. By means of 45 this arrangement it is apparent that with the belt shifter 45 in the position shown in Figs. 1 and 2 and the shield in its corresponding position, the machine is in operation and the fluid which is scraped off of 50 roller 28 passes down over the conductor 37 onto the material passing through the spout 15. It is further apparent that if for any reason it is desired to stop the machine by shifting the belt shifter 45 through the 55 agency of the handle 50, the shield, by means of its connection with the belt shifter 45, is swung simultaneously into the position shown in Fig. 4, thus preventing the fluid from passing down onto the material 60 passing through the spout and directing said fluid into the lower receptacle 19.

It is evident that there may be various modifications of my invention as here particularly shown and described, and it is my 65 intention to cover all such modifications

which do not involve a departure from the spirit and scope of my invention.

What I claim as my invention and desire to secure by Letters Patent is:

1. In a machine for treating fiber, the combination of means for supplying treating fluid to material passing through the machine, and shiftable guide means for changing automatically the course of the fluid when operation of the machine is 75 affected.

2. In a machine for treating fiber, the combination of means for supplying treating fluid to material passing through the machine, and means for diverting the supply of fluid away from the material when the machine is stopped.

3. In a machine for treating fiber, the combination of means for supplying treating fluid to material passing through the machine, and operated means for diverting the supply of fluid away from material when the machine is stopped and to permit the supply of fluid to the material when the machine is set in motion.

4. In a machine for treating fiber, the combination of means for supplying treating fluid to material passing through the machine, and means for simultaneously controlling the operation of the machine and 95 changing the course of a continuous flow of fluid relative to the material passing therethrough.

5. In a machine for treating fiber, the combination of means for supplying treating fluid to material passing through the machine, and simultaneously controlled means for starting the machine into operation and changing the direction of the flow of fluid to the material.

6. In a machine for treating fiber, the combination of means for supplying treating fluid to material passing through the machine, and simultaneously controlled means for starting the machine into operation and permitting the flow of fluid to the material and for stopping the operation of the machine and diverting the flow of fluid away from the material.

7. In a machine for treating fiber, the combination of a movable fluid supplying member, a member for removing fluid therefrom, and a member for permitting or preventing the fluid passing from said last mentioned means to material passing through 120 the machine.

8. In a machine for treating fiber, the combination of a fluid supplying member, a member for removing fluid therefrom, and an automatically controlled member for permitting or preventing the fluid passing from said last mentioned means to material passing through 125 the machine.

9. In combination, a machine for treating fiber, a fluid circulating system, means for 130

removing fluid from said system, and means for permitting or preventing the supply of the removed fluid either to material passing through the machine or back into the circulating system depending upon the operation of the machine.

10. In a machine for treating fiber, the combination of a plurality of fluid receptacles, a roller operating in one of said receptacles for carrying fluid therefrom, a scraper for removing fluid from said roller, and a shield for permitting fluid to pass from said scraper onto material passing through the machine or for directing the flow of fluid into another of said receptacles.

11. In a machine for treating fiber, the combination of a plurality of fluid containing receptacles, means for removing fluid from one of said receptacles, and means for permitting the flow of fluid removed therefrom onto material passing through the machine or directing it into another of said receptacles.

25. 12. In combination, a machine for treating fiber, a fluid circulating system, means to remove fluid therefrom, a fluid conductor, and means permitting or preventing the supply of said removed fluid onto said conductor or back into the circulating system depending upon the operation of the machine.

13. In combination, a machine for treating fiber, treating fluid supply means, a roller for conveying fluid from said means, a scraper for removing fluid from said roller, a fluid conductor, and a shield for controlling the supply of fluid from said scraper either to said conductor for permitting the fluid to pass onto material passing through the machine, or for directing the fluid from said scraper back to said supply means.

14. In a machine for treating fiber, the combination of a plurality of fluid containing receptacles, a roller for conveying fluid from one of said receptacles, a scraper for removing fluid from said roller, means for maintaining said scraper in engagement with said roller, and means for controlling the flow of said fluid from said scraper onto material passing through said machine or into another of said fluid containing receptacles.

In testimony whereof I affix my signature, in the presence of two witnesses.

CHARLES M. GREISING.
